UNITED STATES PATENT OFFICE.

WALTER R. TAYLOR, OF CHICAGO, ILLINOIS.

OIL BURNER.

Application filed July 19, 1920. Serial No. 397,542.

To all whom it may concern:

Be it known that I, WALTER R. TAYLOR, a citizen of the United States, residing at Chicago, in the county of Cook and State 5 of Illinois, have invented certain new and useful Improvements in Oil Burners, of which the following is a description.

My invention belongs to that general class of devices termed oil burners, and adapted 10 to vaporize hydrocarbons, mixing the same with a suitable quantity of air and delivering the mixture at suitable burners, where it may be employed for heating, cooking or other desired purposes.

15 It has for its object the construction of a device of the character mentioned which shall be simple, effective and economical in its construction and effective in its operation. To this end it consists in the novel 20 construction, arrangement and combination of parts herein shown and described, and more particularly pointed out in the claims.

In the drawings, wherein like reference characters indicate like or corresponding 25 parts,

Figure 1 is a top plan view of a simple form of burner illustrating one form of my device;

30 Figure 2 is a vertical section on line 2—2 of Figure 1, illustrating the preferred form of construction of the same;

Figure 3 is a section taken substantially on line 3—3 of Figure 2, showing the receiving chamber;

35 Figure 4 is a section taken substantially on line 4—4 of Figure 2;

Figure 5 is a plan view of a slightly modified form; and

Figure 6 is a fragmentary view illustrating 40 burners arranged at the vertical sides, as well as at the top of the burner.

In the drawings, 1 illustrates the vertical walls of an annular chamber 2, 3 being the top provided with suitable burners 4, and 45 5 indicates the bottom of the chamber. In the center of the chamber is a vertical well or opening 6 enclosed by a circular wall 7. Arranged below the chamber just described is a receiving chamber 8, which in the form

50 shown, at one end is provided with an adjustable cap 9 having formed therein a small orifice 10 through which the vapor is forced. The receiving chamber is also provided with an air chamber 11. The receiving chamber at its air chamber end is 55 held in place by a depending sleeve 12 which

is secured on the bottom of the device, as indicated in Figure 2. A set screw 13, passing through the sleeve 12, serves to maintain the receiving chamber in its proper adjusted position in relation to the intake mixing and fuel pipe 14. The cap 9 also serves a similar adjusting purpose. The feeding and mixing pipe 14 is bent upwardly and backwardly at its other end 15, discharging 60 into the annular chamber 2.

The intake pipe 16 connected with a suitable source of supply under pressure, passes over a portion of the burners as indicated, becoming heated thereby, and passing downward through the central opening referred to (6), at its lower end is connected with and discharges its contents into the receiving chamber 8. The quantity of hydrocarbon oil fed through the pipe 16 may be 70 controlled by a suitable valve, not shown, and the pressure maintained therein in any preferred manner.

The operation of the device as thus described is as follows: The well or pan 17 80 arranged below the receiving chamber may have a small quantity of wood-alcohol or other equivalent material for the purpose poured therein through the central opening 6 and heats the pipe of the receiving chamber. This is lighted and as the oil is gradually admitted, it is vaporized, and by reason of the pressure, the vapor is discharged 85 through the orifice 10 into the open end of the combined feeding and mixing pipe 14. This action draws in a sufficient quantity 90 of air at the open end of the pipe 14 to produce a suitable burning vapor. This is conducted upward and backward, being delivered into the annular chamber 2 and 95 thence escapes through the series of burners 4. The pipe 16 obviously may be heated in any preferred manner, but preferably by being maintained in suitable relation to the burner, and as it becomes heated to a high 100 temperature, the oil delivered therethrough under pressure continues to discharge the vapor downward into the receiving chamber 8, and thence, as described, through the orifice 10.

I have found in actual practice that such burners are inclined to pulsate in their operation, due to the pressure caused by the vaporizing referred to and the varying pressure in the receiving chamber as the pressure therein rises and falls. This may be remedied to a considerable extent by care-

ful feeding. The ordinary operator, however, is often not sufficiently skilled to secure such a result and satisfactory operation is thus not secured.

5 To remedy this undesirable effect, I have provided the air chamber 11 connected with the receiving chamber 8 in any preferred manner. Thus as the pressure rises and tends to cause a pulsating flame, the pressure 10 in the receiving chamber is equalized, that portion of the vapor near the orifice escaping therethrough, and that portion of the vapor more or less compressed into the air chamber, gradually equalizing the pressure 15 in the receiving chamber in the well known manner.

If desired, a series of apertures 18 may be formed in the inner wall of the central well 6, as shown in Figure 2. These also 20 will operate as burners and aid in suitably heating the intake pipe 16.

A similar result may be obtained as indicated in Figure 5, in which the inlet pipe is partially coiled about the upper face of the 25 burner in such a manner as to be subjected to the heat from a larger number of the burners. As shown, the feed pipe 19 is coiled above the burners, finally extending downward as at 20, the result being substantially as set forth.

As shown in Figure 6, a series of burners 21 may be arranged about the vertical wall 1, extending in a horizontal direction. This 35 form is sometimes desirable for heating purposes, increasing the area of the burning section.

Having thus described my invention, it is obvious that various immaterial modifications may be made in the same without departing from the spirit of my invention; 40 hence I do not wish to be understood as limiting myself to the exact form, construction, arrangement and combination of parts herein shown and described, or uses mentioned.

What I claim as new and desire to secure by Letters Patent is:

1. In a device of the kind described, a burner comprising an annular chamber provided with a central well and a series of apertures for the burning vapor arranged in the upper face of the chamber and with one or more apertures arranged in the wall of the central well, a combined mixing and feeding pipe having an open end in free communication with atmospheric air and arranged to convey a mixture of vaporized hydrocarbon and air to the annular chamber, an inlet pipe arranged to extend above the 50 face of the burner and thence through the central well, in combination with a receiving chamber for the vapor operatively connected to the end of the inlet pipe and arranged to discharge the vapor into the open end of the mixing and feeding pipe, and a coop-

erating air chamber for the receiving chamber to equalize the pressure therein.

2. In a device of the kind described, a burner comprising an annular chamber provided with a central well, and a series of apertures for the burning vapor arranged in the upper face of the chamber and with one or more apertures arranged in the wall of the central well, a combined mixing and feeding pipe arranged to convey a mixture of vaporized hydrocarbon and air to the annular chamber, an inlet pipe arranged to extend above the face of the burner and thence through the central well, in combination with a receiving chamber for the vapor arranged below the annular chamber and operatively connected to the end of the inlet pipe, said receiving chamber arranged to discharge the vapor into the open end of the mixing and feeding pipe, and a cooperating air chamber for the receiving chamber.

3. In a device of the kind described, a burner comprising an annular chamber provided with a central well therethrough, and a plurality of apertures in its upper face to constitute burners, a mixing and feeding pipe arranged to convey a mixture of hydrocarbon and air to the annular chamber, and an inlet pipe extending above the upper 95 face of the annular chamber and thence through the central well, in combination with a receiving chamber for the vapor, arranged to discharge the same into the mixing and feeding pipe, means for adjusting the discharge point of the receiving chamber in relation to the mixing and feeding pipe, and a plurality of apertures arranged about the vertical outer wall of the annular chamber, 100 also constituting burners.

4. In a device of the kind described, a burner comprising an annular chamber provided with a central well therethrough and a plurality of apertures in its upper face to constitute burners, a mixing and feeding 105 pipe arranged to convey a mixture of hydrocarbon and air to the annular chamber, and an inlet pipe extending above the upper face of the annular chamber and thence through the central well, in combination with a receiving chamber for the vapor arranged to discharge the same into the mixing and feeding pipe, and a plurality of apertures arranged about the vertical outer wall of the annular chamber also constituting 110 burners.

5. In a device of the kind described, a burner comprising an annular chamber provided with a central web and a series of apertures for the burning vapor arranged in the upper face of the chamber, a combined mixing and feeding pipe arranged to convey a mixture of vaporized hydrocarbon and air to the annular chamber, an inlet pipe arranged to extend above the face of the 125

burner and thence through the central well, in combination with a receiving chamber for the vapor arranged below the annular chamber and operatively connected to the end of the inlet pipe, said receiving chamber arranged to discharge the vapor into the open end of the mixing and feeding pipe.

6. In a device of the kind described, a burner comprising an annular chamber provided with a central web and a series of apertures for the burning vapor arranged in the upper face of the chamber, a combined mixing and feeding pipe arranged to convey a mixture of vaporized hydrocarbon and air to the annular chamber, an inlet pipe arranged to extend above the face of the burner in the form of a coil and thence through the central well, in combination with a receiving chamber for the vapor arranged below the annular chamber and operatively connected to the end of the inlet pipe, said receiving chamber arranged to discharge the vapor into the open end of the mixing and feeding pipe.

25 7. In a device of the kind described, a

burner comprising an annular chamber provided with a central well and a series of apertures for the burning vapors arranged in the upper face of the chamber, a combined mixing and feeding pipe arranged to convey 30 a mixture of vaporized hydrocarbon and air to the annular chamber, an inlet pipe arranged to extend above the face of the burner and thence through the central well, in combination with a receiving chamber for 35 the vapor arranged below the annular chamber and operatively connected to the end of the inlet pipe, said receiving chamber arranged to discharge the vapor into the open end of the mixing and feeding pipe, and a 40 cooperating air chamber for the receiving chamber.

In testimony whereof, I have hereunto signed my name in the presence of two subscribing witnesses.

WALTER R. TAYLOR.
